SPRING ROLLER

Clifford Traut, Newport, Ky., assignor to The Higgin Manufacturing Company, Newport, Ky., a corporation of West Virginia

Application October 29, 1928. Serial No. 315,694

9 Claims. (Cl. 156—39)

My invention relates to spring rollers and particularly to spring rollers for roll screens.

In the art, the use of a hollow roller having a spiral spring within the roller which surrounds a rod extending through the roller is an old and well known mechanism for mounting a window blind or screen. The spring is tensioned by being held fast at one end and having the other end attached to the hollow roller so that as the roller is turned with the removal of the screen or shade the spring is tensioned. When the screen is released the tensioned spring automatically causes the screen to be rolled up on the roller.

It is the object of my invention to provide improvements in the foregoing type of spring rollers which will enforce a smoother and less frictional operation than has heretofore been possible and which will be simple to construct and repair. By eliminating this friction and providing for a normal extension of the spring when unwound, I am able to so arrange that the screen or fabric on the roller is drawn clear up into the box by the spring and has not too great a tension upon it when extended. In the operation of such a device, if the ends of the spiral springs are attached, as has been customary in the past, one to an inner roller rod and the other to the tubular roller and the convolutions extended in mounting the spring so that it can be wound up, that the force exerted by the axial pull of the extended spring will, when the spring is unwound, tend to pull the unattached end of the roller toward the end at which the spring is attached. This results in frictional wear of the operating parts of the roller, particularly at the end adjacent the fixed end of the spring. If, on the other hand, the lengthwise thrust of the spring may be taken up by the rod on which the spring is mounted, then the wear on the roller adjacent the fixed end of the spring will be materially decreased. It is the specific object of my invention to so mount the spring that its lengthwise attenuation and contraction will resolve itself into a pull on the mounting rod for the spring and not on the screen roller.

The above and other objects to which reference will be made in the ensuing disclosure I accomplish by that certain combination and arrangement of parts of which I have shown a preferred modification.

Referring to the drawing:—

Figure 1 is a perspective view of the assembly of roller rod and spring.

Figure 2 is a perspective view from a different angle of the assembly shown in Figure 5.

Figure 3 is a perspective view of the roller and rod, with the bushing attached, showing one type of roller mounting.

Figure 4 is a perspective view of the end of the roller rod, with the bushing attached, showing another type of roller mounting.

Figure 5 is a perspective view of the roller rod and bushing without the spring, showing a modified arrangement for limiting the movement of the bushing on the rod.

In Fig. 3 I have shown my spring roller to be inserted into the usual casing or box, either at the top or the bottom of a window. The roller rod has slots 13 extending into its ends for supporting it in the casing. At one end a pin is secured within the slot 13 thereby preventing the rod 13 from rotating. At the other end a cotter pin may be inserted in a hole extending through the rod.

The spiral spring 15 is mounted on the rod 12. At one end the spring is secured within an end slot 13. The spring is pulled out lengthwise over the rod and its other end bent into hook shape, as indicated at 16, is fastened within the bead 8, as indicated in Figure 3, or it may be attached in a bushing 17 which has a grooved portion 18 into which the exterior wall of the bead fits.

In either event, the spring is extended so that when it has been fully wound up on the round rod that its convolutions will bind against each other. If the spring is not extended axially so that there is space between the convolution it cannot be wound up without lengthening. The bushing is slidable upon the rod, but is limited in its movement on the rod by means of a pin, as indicated at 19 in Figure 2, or a flange 19a on the rod 12 may be provided to limit the movement of the bushing on the rod 12, as indicated in Figure 5.

In either event, the spring connection is automatically adjustable, therefore there will be no lengthwise pull developed to cause a frictional binding of the end of the hollow roller against the inner wall of the casing, and undue strain and wear on the operating parts of the mechanism will be avoided. One end of the spring will be secured in one end of the rod and the other end will be secured in a bushing held in blocked position on the same rod so that no lengthwise pull can be effective on the hollow roller.

Having thus described my invention, what I claim as new and desire to secure by Letters Patent, is:—

105

110

1. In a roller screen, a spring tensioned roller carrying said screen, said roller having a rod extending therethrough, a spiral spring surrounding said rod, said spring fixed at one end to said rod and having a movable driving connection with said roller at its other end, blocking means for limiting the movement of said connection with relation to said rod whereby the lengthwise impulse of said spring will not affect said roller. 80
2. A spring roller mechanism comprising a hollow roller having an inturned bead, a spiral spring extending through said roller, a rod within said spring, means for fixedly mounting said spring at one of its ends to said rod, means for connecting said spring and inturned bead at the other end of the spring, and means for limiting the contracting movement of said spring with relation to said rod. 85
3. A spring roller mechanism comprising a hollow roller having an inturned bead, a spiral spring extending through said roller, a rod within said spring, means for non-rotatably mounting said rod, means for fixedly mounting said spring at one of its ends to said rod and means for connecting said spring and inturned bead at the other end of the spring, said connecting means being slidable to a blocked position on said rod. 90
4. A roller screen operating mechanism comprising a hollow roller, a roller rod, and a coiled spring fixed at one of its ends to said rod having a connection to the roller at its other end for tensioning said roller, and means on said roller rod for limiting the contraction of said spring. 100
5. A roller screen operating mechanism comprising a hollow roller, a roller rod, and a coiled spring fixed at one of its ends to said rod and having a movable connection to the roller at its other end for tensioning said roller, said connection movable lengthwise of said rod, and means on said rod for limiting the movement of said connection on said rod. 110
6. In combination in a device of the character specified, a hollow roller, a roller rod extending through said roller for supporting said roller, and a spiral spring extensible lengthwise of said rod for tensioning said roller, and means for limiting the movement of said spring on said rod. 115
7. In combination in a device of the character specified, a hollow roller, a roller rod extending through said roller for supporting said roller, and a spiral spring extensible lengthwise of said rod for tensioning said roller, said spring having a fixed connection at one of its ends to said roller rod, and an axially sliding connection with said roller at its other end, said connection being slidable in relation to said fixed connection. 120
8. In combination in a device of the character specified, a hollow roller, a roller rod extending through said roller for supporting said roller, and a spiral spring extended lengthwise of said rod for tensioning said roller, said spring having a fixed connection at one of its ends to said roller rod, said roller having an inturned bead and said spring having a sliding connection at its other end with said bead said sliding connection being slidable in relation to said fixed connection. 125
9. In combination in a device of the character specified, a hollow roller, a roller rod extending through said roller for supporting said roller, and a spiral spring extended lengthwise of said rod for tensioning said roller, said spring having a fixed connection at one of its ends to said roller rod, said roller having an inturned bead and said spring having a sliding connection at its other end with said bead comprising a bushing having a recess which said bead engages said bushing being slidable in relation to said fixed connection. 130
